The ornamental design for a combined water filter, flow regulator and shower head, as shown and described.

DESCRIPTION

FIG. 1 is a perspective view of our new design for a combined water filter, flow regulator and shower head; FIG. 2 is a right side elevation view thereof, the left side elevation view being a mirror image;

FIG. 3 is a front end elevation view thereof;

FIG. 4 is a rear end elevation view thereof;

FIG. 5 is a top plan view thereof; and,

FIG. 6 is a bottom plan view thereof.

FIG. 5

FIG. 6
